UNITED STATES PATENT OFFICE.

FRANK H. ANTHONY, OF BROOKLYN, ASSIGNOR TO WILLIAM M. DUCKER,
OF NEW YORK, N. Y.

FIRE-ESCAPE LADDER.

SPECIFICATION forming part of Letters Patent No. 288,756, dated November 20, 1883.

Application filed April 13, 1883. (No model.)

To all whom it may concern:

Be it known that I, FRANK H. ANTHONY, a citizen of the United States, residing in the city of Brooklyn, county of Kings, and State of New York, have invented certain new and useful Improvements in Fire Escapes or Ladders; and I do hereby declare the following to be a full, clear, and exact description of the invention, such as will enable others skilled in the art to which it appertains to make and use the same, reference being had to the accompanying drawings, which form a part of this specification.

My invention relates to that class of fire escapes or ladders which are not required to be permanently adjusted in place, but which may readily be adjusted at any opening, as circumstances require.

The object of my invention is such an adjustable fire escape or ladder, and one that can readily be firmly attached at the place required, that will be light, so as to be easily handled and moved, and that will take up only a small space when not in use, so as to be conveniently stored, and that can be cheaply and easily made, and yet be strong enough to answer all practical purposes.

In the drawings, Figure 1 is a front view of my fire escape in place. Fig. 2 is a side view of the same. Fig. 3 shows the ladder made of three-strand twisted rope. Fig. 4 shows the same made of a four-strand twisted rope. Fig. 5 shows the same made of a three-strand braided rope. Fig. 6 shows the same made of a four-strand braided rope. Fig. 7 is a side view of the hooks *a*. Fig. 8 is a bottom view of the same. Fig. 9 is a front view of the guard *b*. Fig. 10 is a top view of the same. Fig. 11 is a cut section of the same.

a a are hooks or grapnels attached to the upper end of the ladder, made with sharp points to catch into the inner side or wall of the house or building at any place where it is desired to fasten the ladder, and these hold it firmly and securely in place there, and so that it cannot slip sidewise. Similar hooks may also be secured to the other end of the ladder, to catch that end into any convenient object or structure on or near the ground, in order to draw or

hold the ladder away from the building, or steady it when desired. I make this hook or grapnel with two prongs or claws, as clearly shown at the bottom of the ladder in Fig. 1, and also in Fig. 8, because that gives a steady support, and such hooks may also be furnished with the pin or spur *c*, to be driven into the top of the sill or window-frame to further secure and steady the ladder.

b is a guard or protection for the rope, (shown in detail in Figs. 9, 10, and 11,) which is laid upon the window-ledge, and which is provided with the recesses or grooves *b' b'*, into which the rope is laid, such recesses or grooves being made rounding, as shown in Fig. 11, where they pass over the edge of the window-ledge, so that the rope will not be cut or frayed at this point when a weight is upon the ladder. On one side of this guard or protection may be attached springs *e e*, which can be turned back or aside to lay the rope within the grooves, and then adjusted over the rope, and these aid in keeping the rope in position and prevent it slipping off the guard. This guard *b* being loose, can be adjusted to the rope between any of the rounds of the ladder, whereby it is adjustable at the desired place on the ladder, no matter how wide or thick the wall of the building is on which the ladder is to be used. The part of the rope making the turn over the ledge may be further secured against wear and tear by being covered with leather or similar strengthening material, if desired; but this is not necessary when the guard is used; or a portion of the end of the ladder may consist of chains—say a foot or eighteen inches; but that adds to the weight and expense, and I prefer the guard. This guard *b* is so made as to be adjustable anywhere on the sharp edge of a wall or ledge of a window, and can be used with any rope ladder or fire-escape—such as those described in Letters Patent of the United States, Nos. 192,364, 265,531, or 271,796—and will protect the same from being cut by the sharp edge or angle of the wall or window-ledge.

f is the rope out of which the ladder is made, (shown in the drawings as twisted from three and from four strands, and braided from a like number of strands,) and either of the forms of

ropes shown, or other forms, will answer the purpose very well and make a useful structure; but I prefer the braided or twisted rope of four strands as giving the best strength, and 5 the least likelihood of the rounds *d* slipping when inserted between the strands.

The rounds or rungs *d* are made of strong wood, preferably of hickory or similar wood which is tough, are rounded, and have slight 10 depressions turned in them near the ends, at the places where they lie between the strands of the rope, and they are thus secured from slipping on or out of the rope by the knobs on their ends and the thickened part between the 15 ropes. By this form of structure the rounds *d* are held firmly in position in the rope without having to be tied or otherwise fastened or secured there, which makes a ladder thus constructed much lighter than any heretofore 20 known, and saves material and labor as well, and is a great improvement over rope ladders in which the rounds have been generally fastened by wires or other metal clips or rings, which add greatly to the weight and cost of 25 the ladder, and also injure it by rusting.

In the eye or loop *g* of the rope that passes over the ring in the hooks *a*, I splice or secure an ordinary "thimble," so called, to strengthen it.

30 This structure is exceedingly light and strong, can be easily adjusted in any place and quickly

secured there, so that it may be kept in any convenient place on the floor of a building, and then carried to any suitable place farthest removed from the fire, and there firmly and rigidly attached by simply pressing the sharp points of the grapnels *a a* into the wall, adjusting the guard *b*, and throwing the ladder out of the window. It may be supplied to firemen, who can readily carry it on their backs, 35 as a light and suitable means of descent from roofs or other high places in case of necessity. It is conveniently handled and stored, takes up but little space, is simply and cheaply 40 made, and is serviceable for all ordinary purposes in case of fire or other need. 45

Having thus described my invention, what I claim as new is—

1. The adjustable fire-escape described, consisting of a rope ladder provided with hooks 50 or grapnels *a a*, to attach and hold the same in position, in combination with the adjustable guard *b*, to protect the same in crossing sharp edges, substantially as described and shown.

2. The guard *b*, having an angled under portion and a rounded upper bearing-surface, substantially as described and shown. 55

FRANK H. ANTHONY.
